UNITED STATES PATENT OFFICE.

OLUF TYBERG, OF NEW YORK, N. Y., ASSIGNOR TO RUFUS L. PATTERSON AND GEORGE ARENTS, JR., OF SAME PLACE.

CIGAR-MACHINE.

SPECIFICATION forming part of Letters Patent No. 654,195, dated July 24, 1900.

Application filed February 5, 1900. Serial No. 4,073. (No model.)

To all whom it may concern:

Be it known that I, OLUF TYBERG, a citizen of the United States, residing at New York, county of New York, and State of New York, 5 have invented certain new and useful Improvements in Cigar-Machines, fully described and represented in the following specification and the accompanying drawings, forming a part of the same.

10 This invention relates to certain improvements in cigar-machines.

In cigar-machines in which the wrapper is automatically fed to the wrapping mechanism it is desirable to produce a movement between the wrapping mechanism and the device by which the wrapper is held and delivered to the wrapping mechanism—viz., the wrapper-support—by which movement the wrapper is not only fed to the wrapping mechanism, but is so fed that it is smoothly and evenly wound upon the cigar. This movement may be produced by varying the position of the wrapper-support and the wrapping mechanism during the wrapping operation, and the character of the movement varies according to the shape and style of cigar which is to be wrapped. When a cigar of what is known in the art as a "perfecto" shape—i. e., a cigar the greatest diameter of 20 which is at its center and which tapers toward the ends—is to be wrapped, this movement will usually be the resultant of a movement by which the wrapper and cigar to be wrapped are caused to approach each other, 25 this being what may be termed the "approaching" movement, a relative traversing movement by which the wrapper is caused to advance along the cigar, and an angular movement by which the angle at which the 30 wrapper is delivered to the cigar is controlled.

When a cigar of a cylindrical or "panetela" shape is to be wrapped, the angular movement may be either dispensed with or greatly reduced, and if, as is possible, the wrapping mechanism is caused to draw the wrapper from the support without any approaching movement of the two during the wrapping operation this movement may also be dispensed with. Usually, however, the movement 40 between the wrapper-support and the

wrapping mechanism will be the resultant of at least two of the movements referred to, and it may be produced in various ways—that is, by either moving the support or the wrapping mechanism, or both.

One object of this invention is to produce an improved cigar-machine in which the traversing movement by which the wrapper is caused to advance along the cigar can be effected by the movement of the wrapping mechanism.

A further object of the present invention is to produce an improved cigar-machine in which the wrapper shall be carried on a wrapper-support and fed therefrom to the wrapping mechanism, the resultant movement between the two in order to effect the smooth and even winding of the wrapper on the cigar being accomplished by a joint movement of the support and the wrapping mechanism.

A further object of the invention is to produce a cigar-machine of the class above described in which a simple and effective mechanism is used for giving the wrapper-support its desired movement.

A further object of the invention is to produce a cigar-machine of the class above indicated in which a simple and effective mechanism shall be used for giving the wrapping mechanism its desired movement.

A further object of the invention is to produce improved devices for inserting the leading end of the wrapper into the wrapping jaws.

With these and other objects in view the invention consists in certain constructions and in certain parts, improvements, and combinations, as will be described in the following specification and more fully pointed out in the claims hereto appended.

In the accompanying drawings, which form a part of this specification, and in which like characters of reference indicate the same parts, Figure 1 is a plan view of the machine. Fig. 2 is a front elevation. Fig. 3 is an end elevation of the machine looking at it from the right of the observer in Fig. 1. Figs. 4, 5, and 6 are detail sectional views illustrating the construction of the wrapper-support. Figs. 7 and 8 are detail views illustrating the

connection between the wrapping mechanism and the devices for producing the traversing movement thereof. Figs. 9, 10, and 11 are diagrammatic views illustrating successive 5 positions assumed by the wrapper-support and wrapping mechanism during the wrapping operation.

In the machine which has been selected to illustrate a concrete embodiment of the invention, 1 indicates the frame of the machine. The main power-shaft of the machine is marked 2, the shaft being driven by a belt-pulley 3 or in any other suitable manner. The shaft 2 is provided with any suitable form of 10 power-transmitting devices. In the machine shown it carries a worm 4, which engages with a worm-gear 5, said gear being mounted on a cam-shaft 6, which in this machine is a vertical shaft and which carries a series of cams 15 which will be hereinafter referred to.

The machine may be provided with wrapper-cutting devices of any suitable form or description. In the machine shown a hollow cutting-bed 7, the top of which preferably 20 consists of a suction-plate 8, is located on suitable supporting-brackets 9, mounted on the machine-bed. The suction-plate 8 is surrounded by a knife 10, which is given the form of the wrapper which it is desired to cut. Extending from the under side of the hollow cutting-bed 7 is a pipe 11, which communicates with any suitable suction mechanism, such as a suitably-located fan or blower. (Not 25 shown.)

30 In the class of machines to which this machine belongs the operator spreads and stretches a leaf of tobacco on the cutting-bed. The suction is then turned on, and the leaf is held in position while the wrapper is cut therefrom. The suction may be turned on either by hand or automatically. In the present machine the suction is controlled automatically and preferably by a construction 35 which will now be described.

40 To the lower end of the pipe 11 are secured ways 12, in which ways is mounted a slide-valve 13. This valve 13 is operated by means of a valve-rod 14, which reciprocates in suitable bearings 15, depending from the under 45 side of the machine-table. The rod 14 is provided with a collar 16, and between this collar and one of the bearings 15 is located a spring 17, which normally holds the rod 14 in such a position that the valve 13 is drawn back and the suction-pipe is opened, so that 50 the suction is operating through the perforated plate 8. At its inner end the valve-rod 14 is provided with a fork 18, which straddles the vertical shaft 6, before referred to, 55 and the rod is further provided with a friction-roll 19, which bears against a cam 20, mounted on this shaft. The cam 20 is so shaped as to reciprocate the rod 14, and therefore open and close the valve, once for each 60 rotation of the cam-shaft, which rotation is coincident with the cycle of operations in the machine.

Any suitable form of coöperating devices may be used with the knife 10 to effect the cut. In the machine shown a pair of rollers 70 21 is mounted on a pivoted hand-controlled swinging arm 22, said arm being pivoted on a vertical standard 23, suitably mounted on the machine-bed.

The wrapper-support, which serves to take 75 the wrapper from the cutting-bed and present it to the wrapping mechanism, may be variously constructed, and it may be provided with wrapper-retaining devices of any suitable construction. In the present machine 80 the wrapper-support is formed by a hollow casting 24, the operating or wrapper-supporting face of which is formed by a perforated plate 25, the whole forming a suction-support. The perforated plate 25 is preferably provided with a movable section 26, said section being mounted on a transverse pivot or short shaft 27, which finds its bearing in the walls of the chamber 24. Said pivot or short shaft 27 is provided with an upwardly-extending 85 arm 28, said arm being normally held in such position that the section 26 lies in the same plane with the rest of the operating-face by means of a spring 29. This movable section is provided with a lip 30, which serves, when 90 the section is moved downwardly or into the position shown in Fig. 4, to keep the suction-chamber closed. The purpose of this movable section will be hereinafter stated.

95 It will be understood that through the medium of connections hereinafter to be described a suitable suction device is connected with the chamber 24, forming the suction-support. This support serves to take a leaf from the perforated plate 8 of the cutting-bed and thereafter present it to the wrapping mechanism, the leaf being held against the operating-face 25 of the suction-support 100 24 by the suction referred to. While the suction device which has been described is 105 an effective form of wrapper-support, it is to be understood that other retaining devices than suction might be used with the support, or additional devices which coöperate with the suction in retaining the wrapper on the 110 support, either prior to or during the wrapping operation, may also be used.

115 The movement by which the wrapper is delivered from the bed to the support may be effected by moving either the bed or the support, and the movement by which the support is positioned with relation to the wrapping mechanism hereinafter described, so that the support can deliver the wrapper to the wrapping mechanism, may be effected by moving 120 either the wrapping mechanism or the support. The support will, however, preferably be moved into a position where it takes the wrapper from the cutting-bed and will be thereafter moved into a position where it delivers the wrapper to the wrapping mechanism. To this end, therefore, the support will 125 be operated by the mechanism which will now be described, although it is to be under-

stood that the construction by which the support is carried and operated may be widely varied.

In the machine shown the suction-support 5 24 is provided with an upwardly-extending hollow projection 31, said projection being journaled in the end of a hollow arm 32, said arm being provided at its end with a downwardly-projecting hollow boss 33. The hollow 10 upward projection 31 is provided with an opening 34, which communicates with the opening in the hollow arm 32. The projection 31 may be secured to the hollow arm in any suitable manner. It is shown as being 15 secured thereto by means of a collar 35, which embraces a reduced projection or hub on the projection 31 and is held in position by a set-screw 36. (See Fig. 4.) The arm 32 is, as has been indicated, movable. While the 20 movement of the arm may be effected in various ways, it will preferably be accomplished by pivoting said arm. To this end the arm is attached to, preferably by being cast in one piece therewith, a vertical shaft 37, which is 25 mounted in a suitable bearing 38, formed on a bracket 39, which is secured by means of the screws 40, or in any other suitable manner, to the frame of the machine. The upper 30 end of the shaft 37 has an opening which communicates with the opening in the hollow arm 32, and in this opening in the shaft is located a suitable pipe 41, which communicates with any suitable suction device. (Not shown.)

The shaft 37 may be rotated to produce the 35 desired movements of the hollow arm in any suitable manner. Preferably, however, it will be provided with a toothed segment 42, which segment is secured to the lower end of the shaft 37. This segment 42 is engaged 40 and operated by another segment 43, which is carried on an arm 44. The arm 44 is secured to or cast in one piece with a hub 45, said hub being mounted on a short vertical stud or shaft suitably secured to the bed- 45 plate of the machine, the hub being secured in place on said stud or shaft by means of a washer 46 and a screw 47 or in any other suitable manner. From the upper end of the hub 45 extends an operating-arm 48, which 50 carries a roller 49, said roller engaging with a groove in a suitable cam 50, which is mounted on the vertical cam-shaft 6, before referred to. It is obvious that as the cam-shaft 6 revolves its cam 50 will produce a rotary reciprocating motion of the arm 32 through the 55 connections described.

It has already been said that in wrapping a cigar or cheroot of perfecto shape it is desirable to produce a relative movement between 60 the wrapping mechanism and the wrapper-support, which is the resultant of what may be termed a relative "approaching" movement—that is, a movement of the two parts toward each other or a movement of one of the parts 65 toward the other—and by which movement the wrapper is initially fed to the cigar, a traversing movement—that is, a movement of the

two parts across each other or of one of the parts across the other—by which movement the wrapper is advanced along the cigar, and 70 an angular movement of the two parts with relation to each other or of one of the parts with relation to the other, by which movement the angle at which the wrapper is delivered to the cigar is controlled, and by the 75 term "an approaching movement" is not meant that all parts of the support approach the wrapping mechanism during the wrapping operation, since, in the machine shown, that part of the support from which the wrapper has been removed moves away from the wrapping mechanism. That part of the support which still retains the wrapper, however, continues to approach the wrapping mechanism during the wrapping operation, 80 and hence the term "approaching" is deemed 85 a proper one to apply to this movement of the support. It will be readily understood that the relative resultant movement of the movements referred to can be effected by giving 90 a proper movement or movements to either the wrapping mechanism or the support, or to both.

In the machine shown, which is a machine for wrapping cigars of the perfecto shape, the 95 resultant movement above described is produced by giving to the support the approaching movement and the angular movement and by giving to the wrapping mechanism the traversing or cross movement. The approaching movement which the support has is effected through the rotary reciprocating movement of the arm before described.

In order to produce the angular movement, it is necessary to give to the support a movement with respect to its carrying-arm. While this movement might be effected by various constructions, it is preferably effected by causing the upwardly-extending projection 31, which has been before described, to act 105 as a pivot, the support 24 being swung about a vertical axis passing through the center of this projection. The means for producing this pivotal movement of the support may be varied within wide limits. In the machine 110 shown, however, the projection 31 is surrounded by a collar 51, said collar being held in position on the projection by means of a set-screw 52 (see Fig. 4) or in any other suitable manner. The collar 51 is provided with 115 an upward hollow extension 53, said extension being engaged by a downwardly-projecting pin 54, which is carried on a link 55. The link 55 is connected to one of the arms 56 of a bell-crank lever 56 57. This bell-crank lever is journaled on a vertical pivot 58, which is supported in an extension 59, which projects from the side of the arm 32. The arm 57 of the bell-crank lever 56 57 carries a roller 60, which engages with a cam-groove in a cam- 120 plate 61, which is secured by means of screws to vertical standards 62, which rise from the bed-plate of the machine. It will be seen, 125 therefore, that as the arm 32 is given a rotary

reciprocating movement by the means before referred to the cam-plate 61 will, if properly shaped, produce a movement of the support 24 in its bearing 33, which movement will 5 be an angular movement with relation to a wrapping mechanism to be hereinafter described.

The wrapping mechanism by which the cigar is wrapped may be of any suitable construction. Preferably, however, it will be generally of the construction shown and described in United States patent to J. Reuse, No. 552,447, granted December 31, 1895, and more specifically in my application, Serial No. 15 4,075, filed February 5, 1900. Reference to said patent and application is herein made for the specific disclosure of the construction of said mechanism. For the purposes of this application it is sufficient to say that the wrapping 20 is accomplished by means of two pairs of intermeshing jaws 63 64, pivoted on rods. (See Figs. 7 and 8.) The jaws are controlled in their movement by means of rotating rods 65, which work in slots in arms 65', pivoted on a 25 common center. These rods also work in slots in extensions 66 from the jaws 63 64 and operate to produce rotary movements of the jaws about the axis of a cigar as a center. The movements of the rods are produced 30 through suitable gears, the machine being driven by means of a sprocket-chain which engages with a sprocket-wheel 68, mounted on the main shaft 2 of the machine.

Suitable clutch mechanisms will be provided by which the operation of the machine is in general controlled, so as to be started and stopped at suitable times—namely, when a bunch is to be delivered thereto and a cigar removed therefrom. Inasmuch, however, as 40 these clutch mechanisms form no part of this invention they will not be herein described.

It has already been stated that in this machine the wrapping mechanism will preferably be given a traversing movement with 45 respect to the wrapper-support during the wrapping operation. This traversing movement of the machine may be effected in various ways. Preferably, however, the jaws 63 64 will be mounted to slide on their supporting and operating rods, these rods being made long enough so as to permit the movement of the jaws. To effect this sliding movement, one of the jaws, herein shown as the jaw 63, is provided with a grooved block 69. (See 55 Figs. 7 and 8.) This grooved block is engaged by a head 70 on a transverse rod 71, said rod working through the pivotal points of the arms 65'. The block 69 is so located with respect to the point of movement of the 60 jaws that the jaws work only slightly on the head 70 of the rod 71, and this slight movement is provided for by the groove in the block. The rod 71 is connected, preferably by a short link 72, to an arm 73 of a bell- 65 crank lever 73 74. Said lever 73 74 is formed with a sleeve 75, which is mounted on a vertical stud secured to the bed-plate, the sleeve

being secured to the stud by means of a washer 76 and a screw 77 or in any other suitable manner. The arm 74 of the bell- 70 crank lever 73 74 carries a roller 78, which engages with a groove in a cam 79, which is mounted on the vertical cam-shaft 6, before referred to.

In the machine shown the wrapper-support 75 is located over the wrapping mechanism, and therefore moves in a plane above it. While this is a convenient and effective arrangement, it is not an absolutely necessary one, as the parts might be differently disposed. 80 Preferably, however, the support will be arranged to move in a plane which does not intersect the wrapping mechanism, as the parts are thus enabled to have a cross movement during the wrapping operation, and the 85 support is thus positioned so that it can deliver the wrapper very effectively and at the same time control it as the wrapping operation proceeds.

The purpose of rocking the movable section 90 26 of the face-plate 25, which forms a part of the suction-support, is to drop the end of the wrapper into the grasp of the jaws of the wrapping mechanism. In order to effect this, a stop 80 is located over the wrapping mechanism and in the path of the arm 28 of the shaft 27, this stop being carried by a curved arm 81, suitably secured to the bed-plate of the machine. When, therefore, the arm in its swinging movement brings the suction-support into position with relation to the wrapping mechanism when the wrapper is to be delivered to the said mechanism, the arm 28 strikes the stop 80 and throws the movable section 26 down into the position indicated in Fig. 4, thus placing the end of the wrapper in the jaws of the wrapping mechanism.

The construction being as before described, the operation of the machine is as follows: 110 The operator spreads and properly stretches a leaf of tobacco over the plate 8 of the cutting-bed, and as soon as this operation is completed the suction is turned onto the die through the operation of the valve 13, the 115 valve-operating rod 14, and the spring 17. The operator then seizes the handle of the arm 22 and causes the roller 21 to travel over the knife 10, cutting out the wrapper. By the time this operation is completed, the arm 22 120 has been moved out of the way, and the arm 32, carrying the wrapper-support, has been swung, by means of the segment-arm 44, the engaging segments 43 and 42, and the operating parts therefor, into a position where the 125 support is directly over the cutting-bed. It may be here remarked that in this machine the suction is continuously operating on the suction-support, and this is the preferred construction. As soon as the suction-support 130 is squarely over the perforated plate 8 of the cutting-bed the cam 20 operates through the rod 14 to close the valve 13 and shut the suction off from the plate 8. As soon as this

happens, the suction being continuously on the suction-support, the leaf is transferred from the plate 8 to the plate 25, which forms the operating-face of the support. The cams 5 and connections now operate the arm 32 to swing the suction-support into the position indicated in the plan view in Fig. 1 and in the diagrammatic view shown in Fig. 9. As the suction-support comes into this position 10 the arm 28 is operated by the stop 80 and throws the end of the wrapper down into the grasp of the wrapping-jaws, in which a bunch has been placed in any suitable manner. The wrapping-jaws now begin their 15 wrapping operation, and as this proceeds the suction-support is caused to execute what has been herein termed the "approaching" movement, this being effected by the swinging of the arm 32 around its center. As the 20 arm 32 swings the groove in the cam 61, operating through the bell-crank lever 56 57 and the link 55, causes the support to change its angular relation with respect to the wrapping-jaws and at the same time 25 the wrapping-jaws are caused to begin their cross or traversing movement, this being effected by the lever 73 74 and its operating-cam. The positions of the wrapping-support and the wrapping mechanism at 30 about the middle of the wrapping operation and at the end thereof are indicated in the diagrams Figs. 10 and 11. While the wrapping operation is going on, the operator has placed a fresh leaf on the cutting-bed and 35 cuts another wrapper from the said leaf. As soon, therefore, as the wrapping operation is completed the wrapper-support swings into position over the cutting-bed and takes a fresh wrapper therefrom, the wrapped cigar 40 having in the meantime been removed from the wrapping-jaws and a fresh bunch inserted therein.

It is to be understood that the several mechanisms by which the various operations which 45 have been described are carried into effect may be varied within wide limits. The invention is not, therefore, to be limited to the specific mechanisms which have been herein shown and described.

50 What I claim is—

1. In a cigar-machine, the combination with a wrapping mechanism, of a wrapper-support lying in a plane which does not intersect the wrapping mechanism, and means for giving 55 the wrapping mechanism a traversing movement with respect to the support, substantially as described.

2. In a cigar-machine, the combination with a wrapping mechanism, of a wrapper-support located above the wrapping mechanism, and means for giving the wrapping mechanism a traversing movement with respect to the support, substantially as described.

3. In a cigar-machine, the combination with 65 a wrapping mechanism, of a suction-support for the wrapper, and means for giving the wrapping mechanism a traversing movement

with respect to the support, substantially as described.

4. In a cigar-machine, the combination with 70 a wrapping mechanism, of a suction-support for the wrapper lying in a plane which does not intersect the wrapping mechanism, and means for giving the wrapping mechanism a traversing movement with respect to the support, substantially as described.

5. In a cigar-machine, the combination with 75 a wrapping mechanism, of a wrapper-support lying in a plane which does not intersect the wrapping mechanism, and means for giving 80 both the support and the wrapping mechanism co-operating movements in order to wind the wrapper upon the cigar, substantially as described.

6. In a cigar-machine, the combination with 85 a wrapping mechanism, of a suction-support for the wrapper, and means for giving both the support and the wrapping mechanism co-operating movements in order to wind the 90 wrapper upon the cigar, substantially as described.

7. In a cigar-machine, the combination with 95 a wrapping mechanism, of a wrapper-support lying in a plane which does not intersect the wrapping mechanism, and means for producing a relative movement between the support and the wrapping mechanism which is the resultant of an approaching movement, an angular movement, and a traversing movement, this resultant movement being 100 produced by moving both the wrapping mechanism and the support, substantially as described.

8. In a cigar-machine, the combination with 105 a wrapping mechanism, of a wrapper-support lying in a plane which does not intersect the wrapping mechanism, means for giving the support a movement which is the resultant of an approaching movement and an angular movement, and means for giving the wrapping mechanism a traversing movement, substantially as described.

9. In a cigar-machine, the combination with 115 a wrapping mechanism, of a suction-support for the wrapper, means for giving the support a movement which is the resultant of an approaching movement and an angular movement, and means for giving the wrapping mechanism a traversing movement, substantially as described.

10. In a cigar-machine, the combination with 120 a wrapping mechanism, of a wrapper-support, means for moving the support over the wrapping mechanism and at the same time giving it an angular movement with respect thereto, and means for giving the wrapping mechanism a traversing movement, substantially as described.

11. In a cigar-machine, the combination with 125 a wrapping mechanism, of a suction-support for the wrapper lying in a plane which does not intersect the wrapping mechanism, means for giving the support a movement which is the resultant of an approach-

- ing movement and an angular movement, and means for giving the wrapping mechanism a traversing movement, substantially as described.
- 5 12. In a cigar-machine, the combination with a wrapping mechanism, of a suction-support for the wrapper, means for moving the support over the wrapping mechanism and at the same time giving it an angular movement with respect thereto, and means for giving the wrapping mechanism a traversing movement, substantially as described.
- 10 13. In a cigar-machine, the combination with a wrapping mechanism, of a suction-support for the wrapper, means for giving the support an approaching movement with respect to the wrapping mechanism during the wrapping operation, and means for giving the wrapping mechanism a traversing movement during the wrapping operation, substantially as described.
- 15 14. In a cigar-machine, the combination with a wrapping mechanism, of a suction-support for the wrapper which during the wrapping operation is positioned in a plane which does not intersect the wrapping mechanism, and means for traversing the wrapping mechanism with respect to the wrapper-support during the wrapping operation, substantially as described.
- 20 15. In a cigar-machine, the combination with a wrapping mechanism, of a wrapper-support, means for positioning the wrapper-support over the wrapping mechanism, and means for giving the wrapping mechanism a traversing movement with respect to the support, substantially as described.
- 25 16. In a cigar-machine, the combination with a wrapping mechanism, of a suction-support for the wrapper, means for positioning the wrapper-support over the wrapping mechanism, and means for giving the wrapping mechanism a traversing movement with respect to the support, substantially as described.
- 30 17. In a cigar-machine, the combination with a wrapping mechanism, of an arm, a wrapper-support carried on the arm, means for swinging the arm with respect to the wrapping mechanism, and means for traversing the wrapping mechanism with respect to the arm during the wrapping operation, substantially as described.
- 35 18. In a cigar-machine, the combination with a wrapping mechanism, of an arm, a wrapper-support carried on the arm, means for swinging the arm with respect to the wrapping mechanism, means for moving the support with respect to the arm, and means for traversing the wrapping mechanism with respect to the support, substantially as described.
- 40 19. In a cigar-machine, the combination with a wrapping mechanism, of an arm, a suction-support for the wrapper carried on the arm, means for swinging the arm with respect to the wrapping mechanism, and means for traversing the wrapping mechanism with respect to the support, substantially as described.
- 45 20. In a cigar-machine, the combination with a wrapping mechanism, of an arm, a suction-support for the wrapper carried on the arm, means for swinging the arm with respect to the wrapping mechanism, means for moving the support with respect to the arm, and means for traversing the wrapping mechanism with respect to the support, substantially as described.
- 50 21. In a cigar-machine, the combination with a wrapping mechanism, of an arm, a wrapper-support carried on the arm, means for swinging the arm in a plane which does not intersect the wrapping mechanism, and means for traversing the wrapping mechanism with respect to the arm during the wrapping operation, substantially as described.
- 55 22. In a cigar-machine, the combination with a wrapping mechanism, of an arm, a wrapper-support carried on the arm, means for swinging the arm in a plane which does not intersect the wrapping mechanism, means for moving the support with respect to the arm, and means for traversing the wrapping mechanism with respect to the support, substantially as described.
- 60 23. In a cigar-machine, the combination with a wrapping mechanism, of an arm, a suction-support for the wrapper carried on the arm, means for swinging the arm in a plane which does not intersect the wrapping mechanism, and means for traversing the wrapping mechanism with respect to the arm during the wrapping operation, substantially as described.
- 65 24. In a cigar-machine, the combination with a wrapping mechanism, of an arm, a suction-support for the wrapper carried on the arm, means for swinging the arm in a plane which does not intersect the wrapping mechanism, means for moving the support with respect to the arm, and means for traversing the wrapping mechanism with respect to the support, substantially as described.
- 70 25. In a cigar-machine, the combination with a wrapping mechanism, of an arm, a wrapper-support pivoted thereon, a lever pivoted on the arm, a cam for operating the lever, a link connection between the arm and the support, means for swinging the arm on a center, whereby the support is given a movement which is the resultant of the movement of the arm about its center and the movement of the support about its center, and means for traversing the wrapping mechanism with respect to the support, substantially as described.
- 75 26. In a cigar-machine, the combination with a wrapping mechanism, of an arm, a suction-support for the wrapper pivoted thereon, a lever pivoted on the arm, a cam for operating the lever, a link connection between the arm and the support, means for swinging the arm on a center, whereby the support is given

a movement which is the resultant of the movement of the arm about its center and the movement of the support about its center, and means for traversing the wrapping mechanism with respect to the support, substantially as described.

27. The combination with a wrapper-support, the operating-face of which has a movable section, of means for moving said section, and means for retaining the wrapper on the support, substantially as described.

28. The combination with a wrapper-support, the operating-face of which has a movable section, of means for moving said section, and a suction mechanism for retaining the wrapper on the support, substantially as described.

29. The combination with a wrapper-support including a suction-chamber, of a perforated plate closing said chamber, said plate having a movable section, and means for moving said section, substantially as described.

30. The combination with a wrapper-support including a suction-chamber, of a perforated plate closing said chamber, said plate having a movable section, means for moving said section, and means for maintaining the suction in the support after the section is moved, substantially as described.

31. The combination with a wrapper-support including a suction-chamber, of a perforated plate closing said chamber, said plate having a pivoted section, and means for moving said section, substantially as described.

32. The combination with a wrapper-support including a suction-chamber, of a perforated plate closing said chamber, said plate having a pivoted section, means for moving the section, and means for maintaining the suction in the suction-chamber during the movement of the section, substantially as described.

33. The combination with a wrapper-support including a suction-chamber, of a perforated plate closing said chamber, said plate having a pivoted section, means for moving said section, and means carried by said section for maintaining the suction in the suction-chamber during the movement of the section, substantially as described.

34. The combination with a wrapper-support including a section-chamber, of a perforated plate closing said chamber, a short shaft journaled in the sides of the chamber, a movable section carried by said shaft, said section having a projection which closes the chamber when the section is moved, an arm for rocking the shaft, and means for moving the arm, substantially as described.

35. In a cigar-machine, the combination with a wrapping mechanism, of an arm, a suc-

tion wrapper-support pivoted in the arm, a stationary cam, a lever carried by the arm and engaging the cam, a link connection between the lever and the suction-support, means for swinging the arm, and means for imparting a traversing movement to the wrapping mechanism, substantially as described.

36. In a cigar-machine, the combination with a suitable bed, of a cutting mechanism located on the bed, a suction device coacting with the cutting mechanism, a wrapping mechanism located on the bed, a swinging arm located on the bed, a wrapper-support pivoted in the arm, a cam and suitable connections for turning the wrapper-support on its pivot, a vertical cam-shaft located on the bed, a series of cams mounted on the shaft, and suitable connections between said cams and the suction mechanism, the swinging arm and the wrapping mechanism, whereby the said cams control the suction mechanism, move the swinging arm, and impart a traversing movement to the wrapping mechanism, substantially as described.

37. In a cigar-machine, the combination with two pairs of intermeshing jaws, of supporting-rods on which said jaws are pivoted, operating-rods for the jaws, said supporting and operating rods being longer than the jaws, and means for sliding the jaws along the supporting and operating rods, substantially as described.

38. In a cigar-machine, the combination with two pairs of intermeshing jaws, of supporting-rods on which the jaws are pivoted, operating-rods for the jaws, said supporting and operating rods being longer than the jaws, a lever, connections between the lever and the jaws, and means for operating the lever, whereby the jaws are given a lengthwise movement on the supporting and operating rods, substantially as described.

39. In a cigar-machine, the combination with two pairs of intermeshing jaws, of supporting-rods on which the jaws are pivoted, operating-rods for the jaws, said supporting and operating rods being longer than the jaws, an operating-lever, a connecting-rod and a grooved block mounted on one of the jaws to which said rod is connected at one end, and means for connecting the other end of the rod with the operating-lever, substantially as described.

In testimony whereof I have hereunto set my hand in the presence of two subscribing witnesses.

OLUF TYBERG.

Witnesses:

A. L. KENT,
A. A. V. BOURKE.

Corrections in Letters Patent No. 654,195.

It is hereby certified that in Letters Patent No. 654,195, granted July 24, 1900, upon the application of Oluf Tyberg, of New York, N. Y., for an improvement in "Cigar-Machines," errors appear in the printed specification requiring correction, as follows: In line 120, page 4, the word *and* should be inserted before the word "the," and line 121, same page, the word "and" before the word "the" should be stricken out; and that the said Letters Patent should be read with these corrections therein that the same may conform to the record of the case in the Patent Office.

Signed, countersigned, and sealed this 6th day of November, A. D., 1900.

[SEAL.]

F. L. CAMPBELL,
Assistant Secretary of the Interior.

Countersigned:

C. H. DUELL,
Commissioner of Patents.
